UNITED STATES PATENT OFFICE.

WILLIAM D. SMITH, OF TRENTON, NEW JERSEY.

MAIL-BAG CATCHER AND DELIVERER.

1,177,453.

Specification of Letters Patent. Patented Mar. 28, 1916.

Application filed November 2, 1915. Serial No. 59,276.

To all whom it may concern:

Be it known that I, WILLIAM D. SMITH, a citizen of the United States, residing at Trenton, in the county of Mercer and State 5 of New Jersey, have invented certain new and useful Improvements in Mail-Bag Catchers and Deliverers; and I do hereby declare the following to be a full, clear, and exact description of the invention, such as 10 will enable others skilled in the art to which it appertains to make and use the same.

The invention relates to improvements in mail bag catchers and delivering devices.

The object of the present invention is to 15 improve the construction of mail bag catchers and delivering devices and to provide a simple, practical and comparatively inexpensive mail bag catcher and delivering device adapted to support a mail bag in position to be caught by the fork or other device of a train and capable of automatically 20 swinging a mail bag catcher in position for removing the mail bag of a train from the same after the first mentioned mail has been 25 caught by the train.

With these and other objects in view the invention consists in the construction and novel combination and arrangement of parts hereinafter fully described, illustrated in the 30 accompanying drawings and pointed out in the claims hereto appended, it being understood that various changes in the form, proportion and minor details of construction may be resorted to without departing from 35 the spirit or sacrificing any of the advantages of the invention.

In the drawing Figure 1 is a front elevation of a mail bag catcher and delivering device constructed in accordance with this 40 invention, Fig. 2 is a side elevation of the same partly in section, Fig. 3 is a plan view.

Like numerals of reference designate corresponding parts in the several figures of the drawing.

45 In the accompanying drawing in which is illustrated the preferred embodiment of the invention, the mail bag catcher and delivering device comprises in its construction upper and lower mail bag supporting arms 50 1 and 2 pivotally mounted on a post 3 and provided at their outer ends with laterally projecting lugs or supports 4 adapted to receive a mail bag 5. The arms 1 and 2 are provided with upper and lower pivots 6 and 55 7 and they are automatically swung upwardly and downwardly away from each

other by upper and lower coiled springs 9 secured at their lower ends to the post and connected at their upper ends with the upper and lower arms in rear and in advance of 60 the pivots thereof respectively. The upper arm is provided with a rearwardly projecting lug 10 extending beyond the pivot and enabling the upper spring with a downward pull to swing the upper arm upwardly away 65 from the lower arm when the mail bag is removed from the said arms 1 and 2. The lower spring is located below the lower arm and is adapted to swing the same down- 70 wardly.

The upper pivot 6 of the arm 1 is provided at its end opposite that at which the arm 1 is located with a ratchet wheel or member 11 and it supports an arm 12 carrying a hook 13 for catching the mail bag of a car. 75 The hook 13 is formed on the outer end of a rod 14 slidably mounted in guides or eyes 15 of the arm 12 and provided at the inner or upper end with a tooth 16 for engaging the ratchet wheel or member 11. The arm 12 is arranged in a depending vertical position when the arm 1 is in a horizontal position supporting the mail bag 5 and the coiled spring 17 is interposed between the lower ear or eye 15 and a pin 18 of the rod 14 for 80 urging the same upwardly into engagement with the ratchet wheel. By this construction the depending arm 12 is connected with the ratchet wheel and when the mail bag 5 is removed by the device of a car the arm 1 85 will be swung upwardly by its spring and the depending arm 12 will be elevated from a depending vertical position to a projecting horizontal position with the hook 13 in position for engaging the mail bag of a car. As 90 soon as the hook 13 engages the mail bag of the car, the rod 14 will be withdrawn from engagement with the ratchet wheel and the arm 12 will swing downward automatically under the weight of such mail bag. In the 95 operation of the device, the mail bag thereof is put on the train at the first door of a mail car and the hook 13 takes a mail sack or bag from the second door of the mail car. 100

The ratchet mechanism of the mail bag 105 catcher enables the arm 12 to be operated to swing the upper arm downwardly in resetting the delivery device.

What is claimed is:—

1. A device of the class described including upper and lower pivotally mounted spring actuated arms provided with means

for supporting a mail bag, the upper arm being provided with a ratchet member, a pivotally mounted mail catcher arm provided with means for detachably engaging the ratchet member, whereby the mail catcher will be automatically swung into position when the upper arm is released.

2. A device of the class described including a support, a pivotally mounted upwardly swinging mail bag supporting arm, a ratchet wheel connected with the pivot of the said arm, a mail bag catcher arm mounted on the said pivot and a spring actuated hook carried by the mail catcher arm and having a tooth 10 for engaging the ratchet wheel whereby the mail bag catcher arm will be swung upwardly into position when the spring actuated arm is released.

3. A device of the class described including a support, upper and lower mail bag supporting arms, the upper mail bag sup-

porting arm being provided with a pivot mounted on the said support, means for automatically swinging the upper arm upwardly when the same is released by a mail bag, a ratchet wheel mounted on the said pivot, a mail bag catcher arm also mounted on the said pivot and depending therefrom when the upper arm is in its supporting position, a spring actuated rod or member 25 mounted on the mail bag catcher arm and engaging the ratchet wheel whereby the mail bag catcher arm will be automatically swung upwardly when the said upper arm is released, said rod or member being provided 30 with means for catching a mail bag.

In testimony whereof I affix my signature in presence of two witnesses.

WILLIAM D. SMITH
